CARBURETOR DUST CLEANER

Filed July 17, 1929

FIG. 1.

FIG. 2.

Stanley P. Klima,
INVENTOR

BY
Victor J. Evans

ATTORNEY

UNITED STATES PATENT OFFICE

STANLEY P. KLIMA, OF ODESSA, WASHINGTON

CARBURETOR DUST CLEANER

Application filed July 17, 1929. Serial No. 379,048.

This invention relates to certain new and useful improvements in filtering or cleaning devices for the air intake ports of engine carburetors and the like.

An object of the invention contemplates the provision and arrangement of a breather pipe connection for the filter conduit whereby oil fumes and vapor from the crank case will be drawn into the combustion chambers of an engine to lubricate the engine valves, pistons, rings, etc.

An additional object of the invention embodies a deflector for the breather pipe fitting to prevent the drawing off of too much of the oil fumes or vapors whereby qualification of the carburetor adjustment will not be necessary.

With the above and other objects in view, the invention further consists of the following novel features and details of construction to be hereinafter more fully described, illustrated in the accompanying drawing and pointed out in the appended claim.

In the drawing:—

25 Figure 1 is an elevation of my invention as applied for use.

Figure 2 is an enlarged fragmentary sectional view of the breather pipe connection and deflector and conduits.

30 Referring to the drawing in detail wherein like characters of reference denote corresponding parts, the reference character 10 indicates an air cleaner or filter of conventional form having an elbow fitting 11 disposed upon the discharge end thereof. The

35 above construction does not form a part of the invention but is merely shown and will be referred to in the following description of the invention to bring about a better understanding of the exact employment and function of the present invention.

In carrying out the invention, I provide a T-coupling such as indicated at 12 having the vertical leg or depending portion 13 thereof extended or otherwise projected within the uppermost end of a breather pipe 14 upstanding from the crankcase 15 of the engine. One end of the horizontally disposed portion of the T-coupling 12 is in turn fitted in like manner with the remaining end

of the elbow 11 and a flexible conduit 16 provides the means of communication between the coupling and the air intake of the engine carburetor. The T-coupling not only provides a means of support for the elbow, flexible conduit 16 and air filter 10 but also an effective means for introducing and conveying the vapors or fumes from the engine crankcase to the carburetor and thence to the uppermost of the motor mechanisms unfed by the lubricant system of the vehicle.

If the bore of the vertical leg 13 of the T-coupling 12 were left entirely open, too much vacuum or suction would be created through the breather pipe and lubricant in condensed form would be drawn through the flexible conduit, the carburetor and the combustion chambers of the engine. Lubricant in such state or consistency would qualify the carburetor adjustment and foul the spark

70 plugs of the engine. To overcome this apparent difficulty, I provide a deflector in the nature of a sleeve 17 carried within the bore of the vertical leg 13 of the T-coupling 12 adjacent its point of communication with the interior of the horizontal leg of the coupling. A top 18, obliquely disposed upon the uppermost end of the sleeve 17 to provide a restricted opening 19, is projected in the line of draft action from the filter to the carburetor.

75 It is calculated that the opening 19 of this size or its near equivalent will be sufficient to carry off only the fumes or vapors from the crankcase instead of allowing same to be wasted and fill the body of the vehicle with its obnoxious fumes. The sleeve of the deflector 17 is retained against displacement from the position shown in Figure 2 of the drawing within the vertical leg 13 of the T-coupling 12 through the instrumentality of a pin or like fastening 20. By closing the outermost end of the breather pipe to the atmosphere, particles of dust and other extraneous matter will not be drawn into the crankcase upon suction created therein incident to the action of the engine pistons.

80 The invention is susceptible of various changes in its form, proportions and minor details of construction, and the right is herein

reserved to make such changes as properly fall within the scope of the appended claim.

Having thus described the invention, what is claimed is:—

5 The combination of an internal combustion engine having an air filter, of an elbow for the filter projecting from the discharge end thereof, of a T-coupling carried by and supported upon the breather pipe of the engine having connection at its ends with the remaining end of the elbow and the air inlet of the engine carburetor, and a sleeve having an obliquely disposed top arranged within the T-coupling to create suction through the breather pipe whereby lubricant fumes may 10 be drawn through the flexible conduit.

15 In testimony whereof I affix my signature.
STANLEY P. KLIMA.
